J. J. STEINKE.

ELECTRIC SIGN.

APPLICATION FILED FEB. 20, 1917.

1,267,708.

Patented May 28, 1918.

UNITED STATES PATENT OFFICE.

JACOB J. STEINKE, OF FLINT, MICHIGAN.

ELECTRIC SIGN.

1,267,708.

Specification of Letters Patent. Patented May 28, 1918.

Application filed February 20, 1917. Serial No. 149,754.

To all whom it may concern:

Be it known that I, JACOB J. STEINKE, a citizen of the United States, residing at Flint, in the county of Genesee and State of Michigan, have invented certain new and useful Improvements in Electric Signs; and I do hereby declare the following to be a full, clear, and exact description of the invention, such as will enable others skilled in the art to which it appertains to make and use the same.

This invention relates to improvements in electric signs.

The object of this invention is the provision of an electric sign, which is so constructed as to support a plurality of glass panels on which are formed letters of different characters, so that the same is rendered interchangeable.

20 A further object of this invention is the provision of a frame in which is removably placed a plurality of interchangeable letter carrying glass plates, behind which are positioned incandescent lights so that the rays 25 may shine through the plates illuminating the letters thereon.

A further object of this invention is the provision of a frame, and which frame is so constructed as to provide a support for a 30 plurality of glass panels on which are letters of various characters, these panels being interchangeable and adapted to be readily and quickly removed from and replaced in the frame and has located behind or in the rear 35 thereof, incandescent lights which are enclosed within suitable casings so that their rays may be confined therein and directed on the rear of the plates so that the letters on the plates will be illuminated.

40 A still further object of this invention is the provision of an electric sign, which includes a frame in which are adapted to be removably placed a plurality of glass panels on which are arranged letters of various 45 characters, and each letter or character is formed on a separate panel or backing and is adapted to be detachably arranged within the frame and is secured within the frame by a suitable rubber weather strip, and located 50 behind the panels and supported by the frame are casings in which are positioned incandescent lights so as to illuminate the letters on the panels so that the same may be readily read at night.

55 A still further object of this invention is the provision of an electric sign of this

character, which shall be simple, practical and comparatively inexpensive in construction and one that can be manufactured and sold at a small cost.

With these and other objects in view, the invention consists in the novel combination and arrangement of parts as will be herein-after more fully described and set forth in the claims hereto appended.

In the drawings:

Figure 1 is a front elevation of a sign constructed in accordance with my invention,

Fig. 2 is a vertical sectional view of the same,

Fig. 3 is a front elevation of one form of panel carrying the letters or characters,

Fig. 4 is a front elevation of another form of glass panel with the letters of various characters,

Fig. 5 is a fragmentary sectional view of the portion of the weather strip which supports the panels in the frame,

Fig. 6 is a detail fragmentary sectional view illustrating the manner in which the 80 weather strip is secured to the frame,

Fig. 7 is a fragmentary perspective view illustrating the attaching plate carried by one end of one weather strip.

Like numerals of reference designate corresponding parts in all the figures of the drawings.

Referring more particularly to the drawing, the numeral 1 designates an electric sign frame in its entirety and it comprises 90 in its construction a horizontal base bar 2 which bar has its opposite ends turned upwardly as at 3 to constitute attaching members. An arcuate or substantially semi-circular angular bar 4 has each of its ends 95 secured to the upper side of the horizontal bar 2 adjacent the ends thereof, and one of the edges of the angle bars 4 constitutes a stop 5. A semi-circular bar 7 is secured to the upper side of the horizontal base bar 2 100 at each end thereof and is arranged in spaced relation to the angle bar 4, as shown in Fig. 2.

The ends of the semi-circular bar 7 are secured to the upper side of the horizontal base bar 2 at each end thereof and are secured to the opposing faces of the upturned ends 3 of the bar 2, thus rigidly supporting the bar 7 in position. The bar 7 is located directly above the vertical flange 5 of the 110 angle bar 4, thus constituting the front portion of the frame. A horizontal angle bar

8 has each of its ends secured or formed integrally with the angle bar 4 as at 9 and is arranged in spaced relation to the medial portion of the semi-circular bar 4 as illustrated in Fig. 1, thus constituting a second panel receiving frame. A horizontal bar 10 is secured by its ends to or formed integrally with the semi-circular angle bar 4 and is arranged in spaced relation to the angle bar 8 and in a plane above thereof, thus providing a second panel supporting frame. The vertical flange 11 of the angle bar 8 is located directly under the horizontal bar 10 as shown in Fig. 1, the purpose of which will be hereinafter more fully described.

15 The horizontal bar 2 is provided with a vertical flange 12, which flange 12 co-operates with the horizontal bar 13, which bar 13 is secured by its ends to the angle bar 4 adjacent the lower end thereof and in spaced relation to the horizontal supporting bar 2, thus constituting a panel receiving frame.

An arcuate trough member 14 comprising a top wall 15 and bottom wall 16 have 25 their ends connected by the rear wall 17, and constitute a casing. The bottom wall of the casing has its front edge secured to the upper side of the horizontal flange of the angle bar 4 as at 18 and in spaced relation to the vertical flange 5 thereof, thus 30 constituting an annular or substantially semi-circular groove 19. The upper wall 15 of the casing 14 is arranged in spaced relation to the curved bar 7 as shown in Fig. 2, thus providing a semi-circular slot for 35 cooperation with the semi-circular recess 19 and provides a supporting frame in which are positioned glass panels 20.

The glass panels 20 may be colored glass 40 or any other suitable construction and have arranged thereon the characters or letters 21, and these glass panels 20 are substantially wedge-shaped and are arranged between the horizontal bar 7 and the front 45 edge of the top wall 15 of the casing 14 and have their lower ends resting upon the upper side of the horizontal flange of the angle bar 4 and between the vertical flange 5 of the angle bar 4 and the front edge of the bottom wall 16 of the casing and they are adapted 50 to be positioned about the arc of the circle which is formed by the angle bar 4 and the top bar 7, which is substantially semi-circular as clearly illustrated in the drawing.

55 The rear wall 17 of the casing 14 is provided with a plurality of spaced sockets 22, in which sockets are the incandescent lights 23 and these lights are positioned directly 60 behind each of the panels 20 so that their rays may shine through the panels and illuminate the letters thereon.

The casing 14 having a top wall 15, bottom wall 16 and a rear wall 17 is also secured to 65 angle bar 8 and in close proximity to the

horizontal bar 10, thus providing a second casing in which is secured rectangular glass panels 20 having the letters 21 arranged thereon. The operation of placing the panels in the recess formed by the bottom wall 16 and flange 11 of the angle bar 8 is identical with the construction of the bar 4 and the semi-circular bar 7 as previously described.

70 A third casing 14 is also secured to the base bar 2 and in close proximity to the horizontal bar 13, thus providing a third frame for supporting the panels 20, which panels are rectangular and have the letters 21 arranged thereon.

75 The panels 20 are all of a length greater than the depth between the bottom walls of the angle bars and top walls 7, 10 and 13, so that when the panels are positioned in the recesses formed by the bottom wall 16 of the casing, and the vertical flanges of the angle bars, it will be seen that their upper ends project slightly beyond the top wall 15 of the casing and beyond the walls 7, 10 and 13, the purpose of which will be 80 hereinafter more fully described.

An arcuate rubber weather strip 24 is substantially semi-circular in cross section and is provided on its under side centrally of its side edges with a groove 25, which 85 groove is adapted to be arranged over the upper projecting ends of the glass panels 20 and rest upon the upper wall 15 and the arcuate bar 7, as shown in Fig. 2.

90 Secured to the opposite ends of the weather strip 24 are the metal plates 26, which have a depending portion 27 each of which is provided with an opening 28, through which is adapted to extend a set screw 29, securing the weather strip 24 over 100 the upper ends of the glass panels 20 and against the upper casing 14 and arcuate bar 7.

95 A horizontal weather strip 30 is provided on its under side centrally of its ends with a groove 25', which weather strip being substantially semi-circular in cross sections is adapted to be arranged upon the upper edges of the panels 20 arranged in the horizontal frames formed by the angle bars 8 110 and 10 and also by the angle bars 2 and 13, and these strips have embedded in their front sides at the opposite ends thereof the angle attaching plates 31, which permit the horizontal strip 30 to be secured to the bars 115 10 and 13, as shown in Fig. 1.

120 The rubber strips 24 and 30 are removed from the upper edges of the glass panels 20 and the panels are removed from their respective places formed by the various bars, 125 and the name to be used is formed by the various letters and replaced in their respective positions within the frames and the weather strips replaced as described and the device is ready for use, it being under- 130

stood that the incandescent lights 23 are secured to a suitable electric source so that the light rays may penetrate through the glass panels 20 and illuminate the same, it 5 also being understood that the lights can be in an alternating circuit so that the same may go out at various intervals, for the purpose of providing a novel electric sign.

What is claimed is:

- 10 1. An electric sign having a base bar, an arcuate angle bar secured to the base bar, a second bar secured to the base bar and in spaced relation to the first named bar, said last mentioned bars constituting a substantially semi-circular frame, a horizontal angle bar connected with the inner face of the arcuate angle bar, a second horizontal bar connected with the angle bar and in spaced relation to the first named horizontal angle 15 bar and constituting a frame, a plurality of glass panels removably fitted in the frames, and weather strips removably secured to each of the frames upon the upper edges of the glass panels.
- 20 25 2. An electric sign comprising a horizontal supporting bar, arcuate bars secured to the opposite ends of the supporting bar

constituting a frame, horizontal bars secured to the inner arcuate bar and spaced apart forming an auxiliary frame, a plurality of removable glass panels positioned within the frames, and removable weather strips secured over the upper edges of the panels and to the ends of the frames. 30

3. An electric sign comprising a horizontal base supporting bar, spaced arcuate bars secured adjacent each end of the base bar, a casing secured to the rear face of said arcuate bars forming a frame, spaced horizontal bars secured to the inner arcuate 35 bar, casings secured to the rear side of certain of said horizontal bars forming a frame, a plurality of glass panels removably supported in the frames, incandescent lights located in the casings, and weather strips 40 secured over the upper edges of the panels and removably connected to the frames. 45

In testimony whereof I affix my signature in presence of two witnesses.

JACOB J. STEINKE.
